(57) CLAIM

The ornamental design for a clothing strap clip, as shown and described.

DESCRIPTION

FIG. 1 is a perspective view of a clothing strap clip.

FIG. 2 is a front view of the clothing strap clip of FIG. 1.

FIG. 3 is a back view of the clothing strap clip of FIG. 1.

FIG. 4 is left side view of the clothing strap clip of FIG. 1.

FIG. 5 is right side view of the clothing strap clip of FIG. 1.

FIG. 6 is a top view of the clothing strap clip of FIG. 1; and, FIG. 7 is a bottom view of the clothing strap clip of FIG. 1. The broken lines in the figures are for the purpose of illustrating portions of the clothing strap clip and form no part of the claimed design.
